CLAIM

The ornamental design for a container, as shown and described.

DESCRIPTION

FIG. 1 is a top, front, right side perspective view of a container showing a first embodiment of our new design; FIG. 2 is a bottom, rear, left side perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.

The broken lines with short dashes alternating between long dashes define the bounds of the claimed design and form no part thereof. The broken lines with uniform dashes illustrate portions of the environment that form no part of the claimed design.

Shading lines shown in the drawings represent surface contours, or transparency, translucency or opacity, and not surface ornamentation, and such lines, in and of themselves are not part of the claimed design. The shading lines on the surface defined by the elongate vertical slot on the front of the container represent transparency, translucency, or opacity and not surface ornamentation, and such lines, in and of themselves are not part of the claimed design.
